UNITED STATES PATENT OFFICE.

THOMAS W. CRISMAN AND ALEXANDER G. BREHM, OF HASTINGS, NEBRASKA.

ELECTRIC TRAFFIC-INDICATOR.

1,285,052.

Specification of Letters Patent. Patented Nov. 19, 1918.

Application filed April 27, 1917. Serial No. 164,981.

To all whom it may concern:

Be it known that we, THOMAS W. CRISMAN and ALEXANDER G. BREHM, citizens of the United States, residing at Hastings, in the county of Adams and State of Nebraska, have invented certain new and useful Improvements in Electric Traffic-Indicators, of which the following is a specification.

Our invention relates to new and useful improvements in traffic indicators for vehicles and our primary object resides in the provision of an electrically operated traffic or direction indicator which may be controlled by a switch located upon the switch or instrument board of a motor vehicle to indicate to others an intent upon the part of the driver to proceed directly ahead or to turn to the right or left, as the case may be.

In this connection, another object which we have in view is the construction of an indicator by which the signal is given both by signal lights and by a movable indicating member, such as an arrow which may be swung to point in the direction of intended travel. With such an indicator, the movable arrow or other indicating member may be utilized as the sole signal by daylight, while the lights will be largely depended upon as the signaling means at night.

One of the objects of our invention resides in the provision of a signal mechanism inclosing casing adapted to be mounted at any suitable point upon the vehicle and having three spaced bull's eyes, one to be directed toward the front and the others toward either side, and a revoluble shutter within the casing operating in conjunction with a light located within the casing in such a manner that the rays of light will be permitted to pass through one or the other of the bull's eyes, according to the signal to be given.

In this connection, one of the primary objects of our invention consists in providing a novel means for selectively rotating the shutter, together with the direction indicating arrow which is supported by the shutter mechanism, to bring the parts into position to give the desired signal.

Another object which we have in view is to accomplish this movement of the shutter by means of electro-magnets and a latch mechanism in such a manner that the mag-

nets need be energized only while the shutter mechanism is being turned from one position to another, the mechanism being normally held in any selected position by the latch which is released only when the magnets are again energized to change the condition of the signal.

Another object of our invention is the provision of a simple wiring system controlling the magnets so that the signal may be operated by means of a switch conveniently disposed upon the instrument board or other like part of the vehicle.

With these and other objects in view, our invention will be more fully described, illustrated in the accompanying drawings, and then specifically pointed out in the claims which are attached to and form a part of this application.

In the drawings:

Figure 1 is a fragmentary elevation of a motor vehicle, showing our signal device applied thereto;

Fig. 2 is a horizontal sectional view taken through the casing of the signal device, showing the mechanism in plan;

Fig. 3 is a perspective view of the signal device with the casing removed;

Fig. 4 is a fragmentary perspective view, showing the means of supplying current to the main controlling magnet;

Fig. 5 is a bottom plan view of the switch, the supporting base of the switch being removed;

Fig. 6 is a section taken on the line 6—6 of Fig. 5, looking in the direction of the arrows;

Fig. 7 is a perspective view of the movable contact members of the switch and their actuating mechanism;

Fig. 8 is a diagrammatic view of the wiring system employed.

The mechanism proper of our improved traffic indicator is supported upon a circular base 10 of any suitable non-conducting material and is inclosed in a cylindrical casing 11 closed at its upper end and secured to the base by a plurality of brackets 12. Preferably, the upper peripheral edge of the base is cut-away to provide a seat 13 for the lower end of the casing so that the casing will be firmly held against any lateral movement. The casing is preferably formed of some

suitable metal, such as aluminum, and is provided at its front and at either side with bull's eyes 14, the glass of which is preferably of some distinctive color, such as red 5 or green.

Secured to the base and in slightly spaced relation to it by means of brackets 15 is the main supporting frame 16 which includes an arcuate body portion 17 and substantially 10 radially directed terminal portions 18 and 19. Secured to the outer face of the intermediate part 17 of this frame is an upwardly extending bracket 20 carrying inwardly directed vertically spaced arms 21, the inner 15 ends of which journal a vertically disposed shaft 22 which is located centrally of the casing and the upper end of which extends through the top of the casing to receive a direction indicating arrow 23, shown in Fig. 26 1. A collar 24, fixed upon this shaft, rests upon the upper arm 21 to hold the shaft in position and carries a plurality of radially extending arms 25 which, at their free ends, are connected to inwardly directed ears 26 30 formed upon the upper edge of an arcuate shutter 27. This shutter is preferably formed of sheet metal and is supported by the shaft 22 to turn with it, being so held that it may be moved back and forth across the bull's 35 eyes. The opening between the ends of this shutter is of sufficient width to fully expose any one desired bull's eye, but is not long enough to permit exposure of two bull's eyes at the same time. If desired, the shutter 35 may be in the form of a closed ring having a suitable opening capable of being brought into alignment with any desired bull's eye.

An electric light socket 28 is supported between the arms 21 and it will, therefore, be clear that whenever the shutter is moved to bring its opening in alignment with one of the bull's eyes, light rays from an electric light bulb 29 mounted in this socket will pass through such bull's eye. It should further be noted that the direction indicating arrow 23 is so adjusted upon the shaft 22 that it will always point in the direction of the opening in the shutter, that is, directly over the bull's eye which is unguarded by the shutter in any position of the mechanism.

The inner end of the arm 19 of the supporting frame carries inwardly extending vertically spaced brackets 30 which journal the reduced terminals of a shaft 31. A collar 32 fixed upon the upper reduced terminal of this shaft, which is eccentrically disposed within the casing, has a radially extending arm 33 formed with a slot 34 which receives a pin 35 of a crank arm 36 carried by the lower end of the shaft 22. By this arrangement, turning of the shaft 31 will cause turning of the shaft 22 and, consequently, of the shutter and arrow.

As a means for turning the shaft 31 in the desired manner, we provide a main control-

ring electro-magnet 37 which has its pole piece 38 extended at one end into the main body of the shaft 31 and secured therein by a pin 39 so that the magnet is supported by the shaft and extends radially therefrom. 70 The arcuate portion 17 of the frame 16 carries inwardly directed, radially extending electro-magnets 40, 41 and 42 which are concentrically disposed with respect to the shaft 31 so that during turning of the shaft 31, the 75 free terminal of the pole of the electro-magnet 37 will successively pass the inner terminals of the poles of the magnets 40, 41 and 42. The magnet 40, as shown, is located between the magnets 41 and 42 and these 80 magnets are so spaced that when the magnet 37 alines with the magnet 40, the arrow will point directly ahead and the shutter will be in position to permit passage of light through the front bull's eye. On the other 85 hand, when the magnet 37 alines with the magnet 41 the arrow will point to the left and the left bull's eye will be exposed, while when the magnet 37 alines with the magnet 42, as shown in Fig. 2, the arrow will point 90 to the right and the right bull's eye will be exposed.

An L-shaped bracket 43 is secured to the outer face of the arm 19 of the frame and has a lateral arm 44 which supports a vertically disposed electro-magnet 45. An electro-magnet 46 has its pole piece 47 extended beyond its windings at each end and a stud 48 carried by the bracket 43 has a reduced terminal which is passed through the pole piece 47 adjacent the windings of the magnet. A cotter pin 49 or other suitable device holds the pole piece against displacement from the stud and at the same time leaves it and its magnet winding free for turning 105 movement. One end of the pole piece 47 extends into position to form an armature for the magnet 45 and a helical spring 50 connects such end of the pole piece with the base to normally hold it away from the magnet 45. The opposite end of the pole piece 47 is directed upwardly to provide a latch finger 51 which co-operates with a segmental shaped keeper 52 carried by the collar 32. This segmental keeper has a depending 110 flange 53 along its arcuate edge which is formed with a plurality of spaced notches 54 to receive the latch finger 51. These notches are so formed that whenever the electro-magnet 37 is brought into alignment with 115 one of the magnets 40, 41 and 42, which may be termed selector magnets, one of the notches will be in position to be engaged by the latch.

The terminals of the winding of the electro-magnet 37 are brought to spaced contact rings 55 mounted upon the shaft 31 and insulated from the shaft and from each other. A support 56 of insulating material carries spring contact fingers 57 which, at their free 120

ends, engage the contact rings 55, these contact fingers being secured to the support by binding posts 58.

Before describing the wiring of the signaling device and its method of operation, we will describe a compound switch structure by which the various circuits may be controlled. This switch structure is best shown in Figs. 5 to 7 of the drawings and includes a main switch plate 59 and base plate 60 both of suitable non-conducting material, such as fiber, which are secured in spaced relation by means of bolts 61 passed through spacer sleeves 62. A plurality of screws 63 are passed through a spacer strip 64 of insulating material secured to the lower face of the switch plate 59 along one edge and are provided with nuts 65 to form binding posts. These binding posts secure spaced contacts 66, 67, 68, 69, 70, 71 and 72, the ends of which project in spaced relation to the lower face of the plate 59. In like manner, a plurality of screws 73 pass downwardly through the switch plate 59 and carrying nuts 74 provide binding posts which also serve to secure resilient contact strips 75, 76, 77, 78, 79, 80 and 81, which co-operate with the contacts previously named and which extend transversely across the lower face of the switch plate 59, being normally held out of engagement with the contacts through their own resiliency. A push button 82 is mounted for movement through the switch plate 59 and at its lower end has lateral projections 83 which normally seat in a recess formed in the lower face of the plate 59 and which overlie the spring contacts 75 and 76 so that depression of the push button 82 will move both the contact strips 75 and 76 into engagement with their respective contacts 66 and 67. A push button 84 of like type is correspondingly disposed to simultaneously swing the contact strips 77 and 78 into engagement with their respective contacts 68 and 69 and a push button 85 is disposed to simultaneously swing the contact strips 79 and 80 into engagement with their contacts 70 and 71, respectively. Bearing brackets 86, mounted upon the lower face of the plate 59, journal a shaft 87 which is spaced below the contact strips and which carries arms 88 engaging the lower ends of the push buttons 82, 84 and 85 so that depression of any one of the push buttons will cause turning of the shaft. This shaft also carries a further arm 89 having a laterally directed finger 90 which engages above the contact strip 81 so that when the shaft is turned by depression of any push button, the contact strip 81 will be swung into engagement with the contact 72. Binding posts 91 and 92 are secured to the switch plate at one end for connection with the main current supply lines, as will be later explained.

In installing our signal, the signal mechanism proper is mounted upon the top of the radiator or upon one of the mud guards of the vehicle, as shown in Fig. 1, and the wires of its controlling circuits are passed through an armored conduit to the switch mechanism which is located upon the instrument or switch board of the vehicle, as shown at 93 in Fig. 1. Inasmuch as the casing of the signal mechanism is made moisture and dust proof, it will therefore be clear that all injury to any parts or any deterioration through use will be avoided.

In the preferred form of wiring system, wires 94 lead from the terminals of the electro-magnet 40 to the contacts 68 and 69, wires 95 similarly lead from the terminals of the electro-magnet 41 to the contacts 70 and 71, and wires 96 lead from the terminals of the electro-magnet 42 to the contacts 66 and 67. A wire 97 leads from one of the binding posts 58 through which the circuit of the electro-magnet 37 is formed to the contact 72 and a wire 98 leads from the other binding post 58 to one terminal of the electro-magnet 46. A wire 99 leads from the other terminal of this magnet 46 to the contact strip 75 and branch wires 100 lead from the wire 99 to the contact strips 77 and 79. A wire 101 leads from the wire 97 to one terminal of the electro-magnet 45 and a wire 102 leads from the other terminal of this magnet to the wire 99. A wire 103 leads from the binding post 91 to the contact strip 81 and a wire 104 leads from the binding post 92 to the contact strip 76. Branch wires 105 lead from this wire 104 to the contact strips 78 and 80. Current may be supplied from any suitable source of electrical energy, such as a battery 106, through line wires 107 and 108 leading to the binding posts 91 and 92. Wires 109 and 110 lead from the electric light 29 to any suitable portions of the wires 106 and 107 or directly to the battery terminals as most convenient and a manually operable switch 111 is interposed in one of these wires so that the light circuit may be opened and closed at will.

In describing the operation of our improved traffic indicator, we will assume that the indicator is in the condition shown in Fig. 1 and diagrammatically in Fig. 8, which is the normal position it will occupy when the vehicle is traveling straight ahead. The light 29 may or may not be energized, according to whether it is light enough to see the direction arrow or not, the energizing of this light being controlled by the switch 111. No current is flowing through any of the magnets and the signal mechanism is held in position by the engagement of the latch finger 51 in the central notch of the keeper 53. If the driver of the vehicle wishes to turn to the right, he will momentarily de-

press the push button 32 which will bring the spring contact strips 75 and 78 into engagement with their respective contacts 65 and 67 and which will also bring the contact strip 81 into engagement with the contact 72. Under these circumstances, a circuit is formed from the battery 106 through the wire 107, binding post 91, wire 103, contact strip 81, contact 72, wire 97 to the electro-magnet 37, from this magnet through the wire 98 to the magnet 48, from this magnet through the wire 99 to the contact strip 78 from this strip to the contact 66, through the wire 96 to the electro-magnet 49, through this magnet and the wire 95 to the contact 67, from this contact to the contact strip 78 and through the wire 104 to the binding post 92 and through the wire 102 to the battery. At the same time, of course, current will pass from the wire 97 through the wire 101, electro-magnet 45 and wire 102 to the wire 99. It will, therefore, be seen that as long as the push button 32 is held in depressed position, both the electro-magnets 45 and 46 are energized and also the electro-magnets 37 and 42. A simultaneous energization of the electro-magnets 45 and 46 causes the former to strongly attract the pole piece of the magnet 48 and thus insure release of the keeper 58 from the latch 51. The energization of the magnets 37 and 42 will cause the magnet 37 to be drawn into alignment with the magnet 42 which will turn the shaft 51 and, consequently, the shaft 22 to swing the arrow to position to point to the right and to turn the shutter to expose the right hand bull's eye. Upon release of the push button to break the above described circuit, the latch 51 will engage in a notch in the keeper 58 to lock the parts in the desired position. The signal may be reset to point directly ahead by depressing the push button 34 to energize the selector magnet 40 or may be at any time swung to point to the left by depressing the push button 36. It is not believed necessary to trace these circuits as they are similar to the one already traced. It should be noted, however, that the contact strip 81 and contact 78 of the switch control the switch through the latch releasing magnets 45 and 46 and the main actuating magnet 37 and that depression of any of the push buttons always brings this contact strip into engagement with its contact. This insures a release of the latch and an energization of the main actuating magnet 37 every time a push button is pressed to close a circuit to cause selected movement of the indicator mechanism.

Although we have illustrated and described our invention in all its details of construction, it will of course be understood that we do not wish to limit ourselves to such details, but reserve the right to make any changes, within the scope of the claims, without in the slightest degree departing from the spirit of our invention.

Having thus described the invention, what is claimed as new is:

1. In a direction signal, a signal device mounted for turning movement, an electro-magnet having operative connection with the signal device whereby when swung the signal device will be swung, a plurality of selector magnets, each adapted to co-operate with and attract the first magnet, a latch for holding the signal device against turning movement, an electro-magnet for releasing the latch, and means for simultaneously energizing the first mentioned magnet, latch releasing magnet, and any desired one of the selector magnets to cause any predetermined turning of the signal device, said means including a circuit for each selector magnet, a portion of each of said circuits being common to all of the selector magnets and including the first mentioned magnet and latch releasing magnet, independent switches depressible for selectively closing each selector magnet circuit, and a switch in that portion of the circuit common to all the selector magnets depressible to be closed upon closing of any one of the first mentioned switches.

2. In a direction signal, a casing provided with a plurality of bull's eyes, a shutter mounted for turning movement within the casing and capable of exposing any one selected bull's eye alone according to how it is turned, a light within the casing, a direction indicating member mounted for turning movement exteriorly of the casing, and electrical means for simultaneously turning the shutter and direction indicating member whereby the direction indicating member will point over the exposed bull's eye.

3. In a direction signal, a casing provided with a plurality of bull's eyes, a shutter mounted for turning movement within the casing and capable of exposing any one selected bull's eye alone according to how it is turned, a light within the casing, a direction indicating member mounted for turning movement exteriorly of the casing, electrical means for simultaneously turning the shutter and direction indicating member whereby the direction indicating member will point over the exposed bull's eye, means for automatically locking both the shutter and direction indicating member in selected position, and electrical means for releasing the lock.

4. In a direction signal, a casing provided with a plurality of spaced bull's eyes, a shaft mounted for turning movement within the casing and projecting through the top thereof, a shutter carried by the shaft and capable of exposing any one desired bull's eye.

eye, a direction indicating member carried by the shaft exteriorly of the casing, an arm having a depending projection, a second shaft mounted for turning movement within the casing, an arm carried by the second shaft and formed with a slot to receive the projection of the first arm, and electrical means for turning the second shaft through various predetermined angles in either direction and for locking it in selected position.

5. In a direction signal, a casing, a signal shaft journaled in the casing, a direction signaling device mounted upon the shaft, means for adjustably turning the shaft, and means for locking the shaft in adjusted position, the said last mentioned means including a radial keeper operatively connected with the shaft and mounted to swing simultaneously with the turning of the shaft, a latch pivoted at a point intermediate of its ends in a plane beneath the keeper and having its outer end directed upwardly to co-

operate therewith, yieldable means engaging the inner end of the latch for constantly urging it to engage the keeper, and means for releasing said latch.

6. In a direction signal, a casing, a signal shaft journaled in the casing, a direction signaling device mounted upon the shaft, means for adjustably turning the shaft, and means for locking the shaft in adjusted position, said last mentioned means including a keeper, an electromagnet, and a second electromagnet having its pole piece pivoted at a point intermediate of the ends thereof to provide a latch adapted to coöperate with the said keeper, the winding of the second magnet being disposed upon the inner extremity of said pole piece whereby to form a weight thereon gravitating to hold the latch in engagement with the keeper.

In testimony whereof we affix our signatures.

THOMAS W. CRISMAN. [L. S.]
ALEXANDER G. BREHM. [L. S.]
